REINHOLD

United States Patent Office.

WILLIAM GORMAN, OF NEW BRITAIN, CONNECTICUT, ASSIGNOR TO THE RUSSELL AND ERWIN MANUFACTURING COMPANY, OF SAME PLACE.

Design No. 3,578, dated July 13, 1869.

DESIGN FOR THE FACE-PLATE OF A LOCK.

The Schedule referred to in these Letters Patent and making part of the same.

To all whom it may concern:

Be it known that I, WILLIAM GORMAN, of New Britain, in the county of Hartford, and State of Connecticut, have invented a new Design for the Face-Plate of a Lock or Latch; and I do hereby declare that the following specification, taken in connection with the drawings making a part of the same, is a full, clear, and exact description thereof.

In the drawings—

A represents the entire face-plate of a lock;

B, the bolt; and

C, the latch-mortises.

In order to give an ornamental effect to the plate, which, when the lock is placed in its mortise in the door-stile, becomes, when the door is open, exposed to view, I surround the edge of the plate with one or more band-lines, *a*, or channels, sunk in the plate, whereby the distinctive effect of a sunken panel is obtained, without being such.

I also prefer to surround the openings in the plate for the bolt and the latch, with similar band-lines, as shown in the drawing.

The spaces between the edge band-lines and the mortises, may be filled in with ornamental scroll-work.

What I claim as my invention, and desire to secure by Letters Patent, is—

The design for the face-plate of a lock or latch, which consists in surrounding the edge of the plate, or its edge and that of the bolt and latch-mortises, with band-lines or sunken channels *a*, and filling in the spaces with ornamental scroll-work, substantially as herein set forth and shown in the drawings.

WILLIAM GORMAN.
